ABSTRACT

An arrangement for adjusting stitch cams in circular knitting machines. A cam box assembly, having a front and back plate defining a hollow space therebetween, is mounted in the circular knitting machine. An adjusting member is mounted in the cam box and is movable in said hollow space. A pair of setting pins are rotatably mounted in mating bores of the adjusting member, which extend laterally to the movement thereof, and are adapted to coact with springbiased stitch cam supporting members, slidably mounted in the cam box. A micrometer screw is rotatably mounted in an end member of the cam box so that its shank portion extends into the hollow space and the adjusting member is urged against the shank portion by the action of the spring biased stitch cam supporting members.

ADJUSTABLE STITCH CAM

BACKGROUND OF THE INVENTION

The invention relates to an arrangement for adjusting stitch cams in the cam box assembly of circular knitting machines.

In the prior art arrangement for circular knitting machines having two or more needle races in the needle dial and also in the needle cylinder of the circular knitting machine, the stitch cams are generally adjusted on the basis of two different known methods of stitch density control.

According to a first known method, the knitting needles of each knitting system are withdrawn in all races by one stitch cam, and according to the second known method the knitting needles are withdrawn in each race by their own stitch cam.

The first method has the drawback in that all knitting needles are withdrawn, although in some cases the knitting needles are inoperative and do not form loops.

The second method has the drawback in requiring that when it is desired that the knitting needles are to be inoperative in one of the races, the corresponding stitch cams have to be moved into an inoperative position. Thereafter, when the stitch cams are returned to their operative position, an inaccuracy in their setting and in the clearing stroke occurs. Such inaccuracy arises as follows: the stitch cam which is arranged in the track of the inoperative needle thus is to be set into position "zero," that is, into its basic position which is performed manually. For setting the needles into operation it is necessary to reset the stitch cam to make its locking rate exactly agree with the locking rate of other stitch cams in the same feed, which is a very difficult operation. This causes a variation of the stitch size by the individual knitting needles and a deterioration in the quality of the end product. This inaccuracy which is inherent in the prior art designs and is due to the manner of actuating the individual stitch cams by self-contained independent screws or non-circular discs, being particularly sensitive to the amount of angular displacement.

SUMMARY OF THE INVENTION

It is accordingly a primary object of the present invention to eliminate all of the aforescribed drawbacks of the prior art arrangements.

In accordance with the invention, this object is achieved by providing the cam box assembly with an internal hollow space in which a micrometer screw is rotatably mounted in the support of the cam box assembly. A member is adjustably movably mounted in the hollow space of the cam box assembly and has at least two adjustable setting pins disposed perpendicular to the movement of the member. The setting pins can be manually adjusted and comprise means for automatically securing them in the end positions. The pins have half-cylindrical-shaped projections adapted to engage the noses of the stitch cams which are adjustably slidably mounted on guide bars in the cam box assembly. The stitch cams are provided with coil springs urging them to bear against the micrometer screw.

The arrangement of the invention has the advantage that when any one of the stitch cams is inoperative, the corresponding knitting needles are also out of action.

A further advantage of the arrangement of the invention resides in the possibility to adjust some of the stitch cams to render them individually inoperative by moving the setting pin from the operative to the inoperative position, thereby avoiding the rearrangement of the common guide means for the stitch cams of one knitting system.

An especially significant advantage of the arrangement of the invention resides in the possibility of adjusting any preselected stitch cams into the operative position, which corresponds to the position of the respective stitch cam before its setting into the inoperative position. This change of the stitch cam position can be carried out even during the machine operation.

15

BRIEF DESCRIPTION OF THE DRAWING

The arrangement of the present invention is illustrated by way of example in the accompanying drawing which forms part of this application and in which:

20 FIG. 1 is an elevational view of a longitudinal section of the cam box assembly;

FIG. 2 is a sectional view along line II-II of FIG. 1; and

25 FIG. 3 is a plan view of the cross-section of one stitch cam with the setting pin.

DESCRIPTION OF PREFERRED EMBODIMENT

Referring to the drawing, there is illustrated a cam box assembly 1 which includes a rectangular support plate 2, to the side walls of which the front plate 3 and the back plate 4 are fixed by means of screws (not shown). The plates 3 and 4 together with the upper and lower end portions of plate 2, hereinafter called a top plate and a bottom plate, respectively, support plate 2 define the internal hollow space 5 of the cam box assembly 1. A member 6 is slidably movable in the internal hollow space 5 and is urged into contact with a micrometer screw 7 provided with a knob 8 having a scale (not shown). The member 6 has at least two bores in which there are adjustably mounted two mating setting pins 9 and 10. The pins 9 and 10 are cylindrically shaped and have at one end thereof a stepped portion 11 with a lateral slot 12, and at the other end which extends inside of the cam box assembly 1, a projection 13 of a halfcylinder shape by means of which each setting pin 9 and 10 is brought into engagement with one of the stitch cams 14 and 15. The stitch cams 14 and 15 are of a prismatic shape and have a pair of opposite grooves 16 into which matingly fit a pair of guide bars 17 which extend from the front plate 3. The stitch cams are fitted on the guide bars 17, which form the longer sides of the rectangular window 18, as depicted in FIG. 2, in the front plate 3. The stitch cams 14 and 15 have cam surfaces 19 which are situated outside of the cam box assembly 1. The cam surfaces 19 control the movement of the knitting needles (not shown). The stitch cams 14 and 15 are mounted for vertical movement. Simultaneously with the upward movement of the stitch cam 14 and/or the stitch cam 15, respective raising cams (not shown) are put out of operation in a known way. This means that stitch cam 14 and/or 15 is removed from the path of the needles passing the knitting system in their welt position.

65 Each one of the stitch cams 14 and 15 has a recess 20 into which one end of a coil spring 21 extends. The opposite end of the coil spring 21 of the stitch cam 15 bears against a wall 22 fixedly mounted in the internal

hollow space 5 of the cam box assembly 1 and the coil spring 21 of the other stitch cam 14 bears against a partition 23, which is also fixedly mounted in the internal hollow space 5. The coil springs 21 thus act on the stitch cams 14 and 15 to urge them towards the micrometer screw 7.

The stitch cams 14 and 15 have internally projecting noses 24 which are urged into contact with the projections 13 of the setting pins 9 and 10 by the coil springs 21 thereby pressing the member 6 against the micrometer screw 7. A bore 25 extends between the bores for the setting pins 9 and 10 in the member 6. A bore 27' traverses the bore 25 at right angles and accommodates a stud 27. Two coil springs 26 are disposed in the bores 25 and bear with their proximate ends against the stud 27 which extends parallel to the setting pins 9 and 10 and traverses the connecting bore 25. The distant ends of the two coil springs 26 bear against the arresting balls 28 and 29 which serve for rolling into the corresponding recesses 30 and 31 in the setting pins 9 and 10, thereby arresting the pins 9 and 10 in their respective end positions.

The back plate 4, which encloses one side of the hollow space 5 of the cam box assembly 1, is provided with longitudinal slits 32 and 33, through which the stepped portions 11 of the setting pins 9 and 10 outside of the cam box assembly 1 pass and which permits an adjustment of the member 6 jointly with the setting pins 9 and 10. The support plate 2 with both plates 3 and 4 can be mounted so as to constitute a removable assembly which can be inserted into a suitable opening of the cam box assembly 1.

By rotating the knob 8 of the micrometer screw 7 in one direction, an axial displacement of the micrometer screw 7 into the cam box assembly 1 is effected and thereby there is also effected the adjustment of the member 6 with the setting pins 9 and 10 and with their projections 13, which contact the stitch cams 14 and 15 and act on them against the pressure of the coil springs 21. The adjustment of the stitch cams 14 and 15 toward the needle path increases the stitch length drawn by the knitting needles. By rotating the knob 8 in the opposite direction, the member 6 is released and thereby displaced upwardly due to the action of the coil springs 21 by a distance which corresponds to the axial movement of the micrometer screw 7.

Thus by rotating the knob 8, the clearing rate of the knitting needles in all races of the knitting system is adjusted simultaneously. When one of the races is to be adjusted so that the knitting needles are inoperative, i.e., in the case of clearing by one of the stitch cams 14, 15, the adjustment can be simply made by inserting a suitable tool, i.e., a screwdriver, into the lateral slot 12 of the corresponding setting pin, for example, of the setting pin 9, by means of which the pin 9 is rotated and thereby its projection 13 is angularly displaced so that the stitch cam 14 moves into the created free space with its nose 24 due to the pressure exerted by the coil spring 21. The stitch cam 14 is, during its movement, guided by guide bars 17 which project into the opposite grooves 16 disposed in the stitch cam member. The cam surface 19 of the stitch cam 14 is thus brought into an inoperative position. The rotation of the setting pin 9 is automatically arrested in a predetermined position by means of the arresting ball 28, which rolls into the corresponding recess 30 in the setting pin 9 due to the action of the spring 26.

Similarly it is possible to make the other stitch cam 15 inoperative as it is shown in FIG. 1. This can be done by means of the other setting pin 10 which coacts with the stitch cam 15 for clearing the knitting needles of the following race.

When the knitting needles in one of the races is to be returned to the operative position, the corresponding setting pin 9 or 10 is rotated in the described manner in the opposite direction so that the projection 13 disappears during its annular movement the corresponding stitch cam 14 or 15 by contacting the nose 24 thereof and urging it against the pressure of the coil spring 21 exactly back to the initial position.

The invention is particularly useful in cam box assemblies of circular knitting machines where it is essential to maintain a uniform loop size in the knitted fabric after resetting the stitch cams into their operative positions.

Although the invention is illustrated and described with reference to one preferred embodiment thereof, it is to be expressly understood that it is in no way limited to the disclosure of such a preferred embodiment, but is capable of numerous modifications within the scope of the appended claims.

What is claimed is:

1. An arrangement for adjusting stitch cams in circular knitting machines, comprising in combination, a cam box having a front plate and a back plate each having at least one opening, said plates defining a space therebetween, and having a top plate and a bottom plate; a member having at least two transverse bores is movably mounted in said space; a corresponding number of stitch cam setting pins adjustably mounted in said transverse bores; a corresponding number of stitch cams adjustably mounted in said cam box and being adapted to coact with said setting pins; screw means threadably mounted in said top plate and extending into said space so as to contact said member; biasing means disposed in said cam box and urging said member into contact with said screw means; the position of said member including the setting pins relative to the distance from the top and bottom plates is adjustable by said screw means, whereby an adjustment of each stitch cam can be made via the coacting setting pin provided the corresponding setting pin is in its operative position, said stitch cams being individually settable into operative or inoperative position by the turning of said setting pins.

2. The arrangement as set forth in claim 1, wherein said member includes an additional bore disposed between and parallel to said two transverse bores, a pair of bores respectively perpendicularly extending from said additional bore to said two transverse bores, a stud mounted in said additional bore, a pair of coil springs respectively mounted in said pair of perpendicularly extending bores, a pair of stop balls disposed in said perpendicularly extending bores between said coil springs and said setting respectively, each of said setting having at least one recess for accommodating a stop ball so that the adjusting movement of said setting is arrested when said stop ball enters said recess.

3. The arrangement as set forth in claim 1, wherein said setting pins and said stitch cams have projections

which are adapted to coact with each other, so that an adjusting movement of a pin will effect an adjustment of the corresponding stitch cam in said cam box.

4. The arrangement as set forth in claim 3, wherein said setting have screwdriver-receiving portions which

extend through said opening outside of said cam box so that said setting can be manually adjusted by means of a screwdriver.
